CONTACT SPRING SET

Harald Valdemar Alexandersson, Lidingo, Sweden, assignor to Telefonaktiebolaget L M Ericsson, Stockholm, Sweden, a corporation of Sweden

Filed Apr. 23, 1957, Ser. No. 654,514

Claims priority, application Sweden May 5, 1956

9 Claims. (Cl. 200—166)

The invention relates to sets of contact springs for electromagnetic relays and other electromagnetic switching devices.

Contact spring sets for electromagnetic relays are usually provided with contact springs of the flat type. Spring sets have also been made with wires as contact springs. By bending the wires differently it is achieved that the different contact springs may press against each other with suitable contact pressures. However, in manufacture it is troublesome to obtain the right contact pressures and for a few types of contact springs it is also difficult to obtain a great variation of contact combinations. A simple and cheap manner of obtaining a contact spring set, which requires a small adjustment and which provides a very great diversity of contact combinations with only one design of the contact spring, is the object of the invention described below.

The contact spring set is built up by suitably elastic, straight wires, which at their movable ends are forming contact with a rigid contact device, which preferably has no outer fixed connections. The contact pressures between the wires and the rigid contact device is obtained in such a way that the contact wires at the mounting are brought out of their non-tensioned condition to a position either above or below the rigid contact device, so much that, when resting against the device, they give a suitable contact pressure. Desired contact combinations are obtained in such a way that the rigid contact device, which for each type of relay may be of a standardized design, during the mounting of the spring set, by punching out of holes or recesses, is given the contact combination which is desired for said relay. The rigid contact device consists suitably of a bar of insulating material, to which a metal strip has been fixed, which is so shaped that by means of recesses through the metal strip it obtains the desired contact combination. The contact spring set is furthermore provided with a lifting bar of insulating material with two rows of holes or grooves, the upper row of which is intended for contact springs, which produce breaks and the lower row for contact springs, which produce makes. By making the grooves in the lifting bar sufficiently great it is possible to achieve that a contact spring either is not at all operated or that it is operated later than the other contact springs during the movement of the relay.

The contact spring set may either be made with the contact springs located in one plane and the free ends of the wires may thereby be arbitrarily placed above or below the rigid contact device, or with the contact wires located in two parallel planes, the free ends of the upper wires thereby being all located above the rigid contact device and the free ends of the lower ends all located below the rigid contact device.

The invention will now be described more in detail with reference to the annexed drawing. Fig. 1 shows a side view of a relay with a contact spring set, Fig. 2 the same relay seen from in front, Fig. 3 is an enlarged view

2

of the contacts and Fig. 4 is an enlarged illustration of an altered design of the rigid contact device.

On a normal knife-edge relay with a relay angle bar 1, an armature 2, a relay core and a winding 3 there is 5 located a contact spring set. This latter consists in the shown example of seven contact springs 4 fixed in one end to a plinth 5 of insulating material, a plate 6 supported by the plinth, a rigid contact device 7 and a lifting bar 8, which upon movement of the armature 10 operates the springs 4. The rigid contact device consists of a bar of insulating material 9 mounting a metal strip 10. The metal strip is cemented at the bar and is at its edge provided with wedge-shaped contact points 11, at which the contact springs are making contact. The contact springs, which suitably consist of elastic, in non-tensioned condition straight wires, are at their movable ends in the contact point provided with tubes of contact material 12, a twin contact effect thus being obtained when the contact tubes rest in the wedge-shaped contact points 11. When the fixed, elastic contact wires at the 15 mounting are brought to a position either above or below the rigid contact device 7, they must be bent so much from their straight, non-tensioned condition, that they obtain a suitable contact pressure when resting against a contact point 11. The rigid contact device is held in its 20 position by being stretched between two arms 13, which extend from the plate 6. The lifting bar 8 is fixed between two springs 14, 15, which also extend from the plate 6. The lifting bar is provided with two rows of 25 holes or grooves 16, 17, through which the contact wires 4 protrude. The spring 14 is given so strong a pressure downwards that it can overcome the up-pressure from all contact wires brought through the lower row of 30 grooves 17. Normally all wires or springs 4 in the upper row will in non-operated condition rest against the rigid contact device and all springs 4 in the lower row will be kept by the lifting bar 8 at a certain distance from the rigid contact device. Upon operation of the relay 35 the armature operates the lifting bar, which is moved upwards. Then the springs 4 in the upper row are deflected out of engagement and the springs 4 in the lower row follow the movement upwards until they stop, pressed against the rigid contact device by their own spring tension. If certain of the grooves 16, 17 in the lifting bar 40 are made a little larger it will be possible to achieve that the corresponding springs 4 either will be not at all operated by the lifting bar or later than the other springs. Not operated springs 4 are used as fixed connections to the contact device and springs 4, which are operated late, 45 may be used to produce delayed contact functions.

The metal strip 10 on the bar 9 is slotted between each two adjacent notches 11. The slots 18 extend from opposite longitudinal edges of the strip so as to form narrow bridges 10' between each adjacent pair of notches 55 11. By severing selected ones of these bridges by means of holes 19, several effective preselected contact combinations may be obtained when bar 8 is actuated. This affords the advantage that the manufacture of the contact device may be standardized and the device adjusted 60 for a desired contact combination after manufacture. In the example according to Fig. 2, holes 19 are cut, counting from the left of the figure, between the third and fourth contact notches and between the fifth and sixth. The effective contact combination can be further varied 65 by varying the depths of grooves 16. In the example, the grooves 16 for the first and fifth springs are so deep that the first and fifth springs cannot be operated by the lifting bar 8 and will thus remain in the notches 11. The groove 17 for the sixth spring is also so deep that 70 this spring will remain in its notch 11. With such adjustment, upon upward movement of the bar 8, there

will be effected at the second and third notches, counting from the left, a switching, at the fourth notch a make, and at the seventh notch a break. Hence, the circuit between the first and the second spring is broken and switched to a circuit between the first and the third spring, a circuit between the fourth and fifth springs is made, and a circuit between the sixth and seventh springs is broken.

In the embodiments described, all the contact wires 4 are secured to the plinth 5 in one plane. As stated before, all the wires are initially straight, and each individual wire, during assembly, may be placed as desired into either its respective upper notch 11 and groove 16 or lower notch 11 and groove 17. The contact combinations thus obtainable, can be freely selected as required. It is to be noted that only one type of contact wire is required. The total number of contact points is, of course, limited by the practical width of the relay.

While in the embodiment heretofore described, the contact wires are all mounted in one plane, the contact wires may also be mounted in two planes so that each pair of opposite notches 11 has assigned thereto a respective wire. As shown at the left in Fig. 4, the upper row of wires passes through the upper row of grooves 16, Fig. 3, in the lifting bar and the lower row is placed in the lower row of grooves 17. The possibility of varying selectively the possible contact combinations is then somewhat limited, but still considerably greater than by means of the known constructions. When each notch has a respective wire 4, the metal strip for the fixed device 7 can be formed as shown in Fig. 4. In such arrangements the contact wires can be disposed to effect many combinations, the only limitation being that it is not possible to use the wires in the upper row as make contacts and the wires in the lower row as break contacts. The contact combinations in this case are obtained by severing bridges such as 41, 42 in the metal between the contact points. Thus, if the narrow bridges at 41 and 42 are cut, the two wires located farthest to the left in the upper row may, together with the wire located farthest to the left in the lower row, be used for a switching similar to that described in connection with Fig. 2. The second wire in the lower row is connected with the other contact points to the right by way of the bridge 43 and may therefore be included in other combinations.

The invention is of course not limited to the construction described here. It may advantageously be used in the majority of known relay constructions and also for switches or the like. The used contact springs are shaped as round wires. Of course these may be designed in different ways without departing from the principle of the invention. The round wires have proved to be very suitable, but other springs, particularly such that take up small room laterally, may be used, if during the mounting they give a suitable contact pressure when resting against the rigid contact device.

I claim:

1. A set of contact springs for an electromagnetic switching device, said set comprising several flexible springy wires, a mounting means fixedly mounting said wires at one end in coplanar relationship, a stationary contact device including an elongated conductive member extending transversely of the plane of said wires and having contact points at opposite longitudinal sides, one for each contact wire, said wires being flexed out of said plane and overlying contact points on opposite sides of said device to bias the overlying wire portions toward the respective contact points with pressure contact for connecting the wires through said member, and a lifting member displaced transversely of said wire plane, said member being engaged with the flexed wires for transverse movement of the latter in unison with the lifting member whereby a transverse displacement of the member varies the operational positions of said overlying wire portions relative to the respective stationary contact points correspondingly.

2. A set of contact springs according to claim 1 wherein said contact points on the stationary conductive member are of substantially V-shaped cross section and face in opposite directions.
3. A set of contact springs according to claim 1 wherein said stationary conductive member includes recesses between the contact points which recesses underlie the positions occupied by the wires in relation to the stationary contact points in response to a displacement of said lifting member.
4. A set of contact springs according to claim 1 wherein said stationary contact device comprises an insulation-backed metal strip mounting at each end said contact points, said strip being divided in selected electrically separated portions connected to contact points, the selection of the division of said metal strip controlling the contact connections effected by displacement of said lifting member.
5. A set of contact springs according to claim 1 wherein said lifting member comprises an axially displaceable insulation bar having two longitudinally spaced rows of grooves, one for each wire, the grooves of said rows holding in one displaced position of the bar selected wires in pressure contact with contact points at one end of the contact device to form break contacts and other selected wires in disengagement from the contact points at the other end of the contact device to form make contacts and in another displaced holding break contacts in the disengaged position and make contacts in the engaged position.
6. A set of contact springs according to claim 5 wherein selected ones of the grooves associated with break contact wires have a longitudinal length such that the respective wires remain in the contact engaging position upon displacement of the lifting member whereby said break contacts constitute operationally permanent contact connections.
7. A set of contact springs according to claim 5 wherein selected ones of said grooves have a longitudinal length different from that of other selected grooves whereby displacement of the wires in relation to the said contact points is staggered upon displacement of said lifting member.
8. A set of contact springs according to claim 5 wherein said mounting means support said contact wires in two superimposed but spaced apart parallel planes, the wires in one plane engaging the grooves in one row and the wires in the other plane engaging the grooves in the second row, all the wires in one plane forming break contacts and all the wires in the other plane forming make contacts.
9. A set of spring contacts according to claim 8 wherein said stationary contact device comprises a metal strip mounting said contact points along its two longitudinal edges, said strip having slots extending transversely from both longitudinal edges between each two contact points and each terminating short of a slot extending from the respective opposite longitudinal edge and said strips further including apertures between each two contact points situated between the respective inner slot ends, the strip material between the slots and the apertures constituting readily severable bridges, severance of selected ones of said bridges controlling the combination of contact connections effected by displacement of said lifting member.
